United States Patent Office

Des. 229,598
Patented Dec. 18, 1973

229,598

FRAME FOR A HAMMOCK

James L. Westrich, Algoma, Wis., assignor to Gleason
Corporation, Milwaukee, Wis.

Filed Apr. 3, 1972, Ser. No. 240,892

Term of patent 14 years

Int. Cl. D6—06

U.S. Cl. D6—198

Fig. 1

Fig. 2

FIG. 1 is a side perspective view of the improved frame
for a hammock comprising the invention; and
FIG. 2 is an end perspective view of said frame.

I claim:

The ornamental design for a frame for a hammock, as
shown.
